[57] CLAIM

The ornamental design for a pressure welding burner,
substantially as shown.

DESCRIPTION

FIG. 1 is a top perspective view of a pressure welding
burner showing my new design;
FIG. 2 is a top plan view thereof;
FIG. 3 is a bottom plan view thereof;
FIG. 4 is a side elevational view thereof (the opposite
side being a mirror image thereof);
FIG. 5 is a rear end view thereof; and
FIG. 6 is a front end view thereof.

FIG. 1

FIG. 4

FIG. 5

FIG. 6
